UNITED STATES PATENT OFFICE.

JOHN B. HADAWAY, OF BROCKTON, MASSACHUSETTS, ASSIGNOR OF ONE-HALF TO MORRILL E. BRIGGS, OF SAME PLACE.

MACHINE FOR CHANNELING AND TRIMMING BOOT-SOLES, &c.

SPECIFICATION forming part of Letters Patent No. 419,247, dated March 31, 1891.

Application filed December 22, 1890. Serial No. 375,431. (No model.)

To all whom it may concern:

Be it known that I, JOHN B. HADAWAY, of Brockton, in the county of Plymouth and State of Massachusetts, have invented certain new and useful Improvements in Machines for Channeling and Trimming Boot or Shoe Soles, of which the following, taken in connection with the accompanying drawings, is a specification.

- 10 My invention relates to machines for channeling boot or shoe soles and trimming the edges thereof after said soles are secured upon the lasted uppers and the last; and it consists in certain novel features of construction, 15 arrangement, and combination of parts, which will be readily understood by reference to the description of the drawings and to the claims hereinafter given and in which my invention is clearly pointed out.
- 20 Figure 1 of the accompanying drawings is a plan of a machine embodying my invention. Fig. 2 is a front elevation of the same with the base portion of the supporting-column broken away. Fig. 3 is a side elevation of the same, 25 looking toward the left of Figs. 1 and 2, with a portion of one of the shaft-supports broken away. Fig. 4 is a vertical section on line 2 2 on Figs. 1 and 2. Fig. 5 is a section through the lever and slide which carries the channel-30 cutting knife and its stock on line 3 3 on Fig. 4. Fig. 6 is a partial section of the channel-knife-carrying slide and its lever on line 4 4 on Fig. 4 and showing the channel-knife and its stock in front elevation. Fig. 7 is a plan 35 of the channel-knife-carrying stock. Fig. 8 is a section of the same on line 5 5 on Figs. 6 and 7. Fig. 9 is a rear elevation of said knife-stock. Fig. 10 is a side elevation of the same viewed from a standpoint at the right of Fig. 40 9. Figs. 11 and 12 are respectively an inside elevation and an inverted plan of the clamp-plate for holding the upper trimming-knife, and Fig. 13 is a side elevation of the channel-cutting knife. Figs. 6, 7, 8, 9, 10, 11, 12, and 45 13 are drawn to a scale twice as large as the other figures.

In the drawings, A represents the upper portion of a column of suitable height, upon which the base-plate B of the head of the ma-

chine is secured by means of the bolts a a. 50 (See Fig. 2.)

The base-plate B has formed integral therewith the upwardly-projecting block B' and the ear B², and has secured therein upon opposite sides of the column A the standards C 55 and C' in bearings, in the upper ends of which is mounted the shaft D, upon which are firmly secured between said bearings the cam-cylinder E and the cam-disk F, and outside of the standard C the driving-wheel G, grooved to receive a round driving-belt. (Not shown.) The ear B² has pivoted thereto at b the lever H, which is forked so as to straddle said ear, and has secured thereto the work support or table c, which also serves as a gage for guiding the work by bearing at its front end against the upper just beneath the sole, the shoe being inverted or placed in the machine with the tread-surface of the sole upward.

The lever H engages at its end opposite the 70 free end of the work support or table c with a fork c', formed in the upper side of the bar H' at its front end, and has mounted thereon the roll d, with which the hand-lever d', pivoted at d², engages to move said lever H about 75 its fulcrum in one direction. The bar H' is fitted to slide in a bearing e, secured to the bed-plate A, and is moved toward the front of the machine by the tension of the spring e', adjustably secured at one end to said bar 80 H' and at its other end to a pin or stud e², set in the bed A, the forward movement of said bar H' and the upward movement of the free end of the work-support H being limited by the stop-pins f and f' coming in contact or any 85 other suitable stop, all as shown in Figs. 1 and 3. The bar H' has secured upon its upper side two ratchet-plates g and g', the shouldered ends of the teeth of which face toward each other, as shown in Fig. 3. 90

J is a T-shaped or three-armed lever pivoted at f² to the ear B² and carrying at the end of its long arm a roll g², which fits into and is operated upon by the cam-path g³, formed in the side of the disk F to vibrate 95 said lever. The two shorter arms of the lever J have their ends forked, and have pivoted in each of said forks two pawls h and h'

of slightly-different lengths, the points of which are pressed downward by springs i , said downward movement relative to the lever J being limited by the stop-screws i' , as shown in Fig. 3.

- 5 K is an elbow-lever pivoted at d^2 to the ear B^2 and carrying at its upper end a roll h^2 , which rests upon and is acted upon by the face-cam surface formed upon the periphery 10 of the disk F, and at its front end the presser-foot h^3 , which has set in its lower or operating end the spur i^3 to enter the sole when the presser-foot is forced down upon the surface thereof, and thus aid in holding the sole firmly 15 15 while the channel-knife is being moved to cut the channel, said spur being so arranged as to operate upon the sole in the same plane as the trimming-cutters, to be hereinafter described.
- 20 The sole-edge is trimmed to a uniform distance from the upper on the last by means of two trimming-cutters arranged to act upon the sole from opposite sides thereof and meet between the upper and lower surfaces of the 25 sole. The lower trimming-knife j is mounted in the front end of the lever L, mounted upon the fulcrum-pin b , and carrying at the end of its rear or long arm a roll which fits into and is acted upon by the cam-path l in the side of 30 the disk F opposite to the path g^3 and shown only in dotted lines in Fig. 3. The knife j is secured to the lever L by means of the clamping-plate j' and suitable binding bolts or screws, the inner faces of the lever and clamping-plate j' having formed therein curved 35 grooves having beveled bottoms to fit corresponding surfaces on the edges of the knife.

- The block B has formed in its front face a horizontal groove, in which is fitted, so as to 40 be movable endwise therein, the bar L' , having a T-shaped cross-section, and having formed thereon, near its inner or right-hand end, the outwardly and upwardly projecting ear L^2 , to which is pivoted the lever M by 45 means of its two ears k and the stationary fulcrum-pin k' , said bar being held in position in its bearing by the cap-plates l' , as shown.

- The bar L' has a reciprocating motion 50 imparted thereto in the direction of its length by means of the lever N, fulcrumed upon a stud m , set in the front face of the block B' , and having formed therein the rectangular slot m' to receive the block m^2 , mounted upon 55 a stud set in the bar L' , and the cam-path m^3 , formed in the periphery of the cylinder E, which acts upon the truck m^4 , carried by a stud set in the upper end of said lever N, as shown in Figs. 1, 2, and 4. The rear arm of 60 the lever M carries at its end a roll n , which fits into and is acted upon by the cam-path n' , formed in the right-hand end of the cylinder E, as shown in Fig. 4.

- The front arm M' of the lever M is made in 65 the form of a segment of a disk, and has formed therein a rectangular segmental groove, in which is fitted, so as to be movable endwise

therein, the curved slide O, held in position therein by the cap-plate O' and the screw-stud n^2 , set in the back or inner side of said slide and projecting through a slot in the segment M' and the nut n^3 and check-nut n^4 , as shown in Figs. 1, 2, and 4.

The plate O' has cut through it a slot o , through which projects the stud or pin o' , 70 screwed into the outer face of the slide O to receive one end of the spring o^2 , the other end of which is secured to the screw head or stud o^3 , set in the cap-plate O' , as shown in Figs. 1, 2, and 4, the tension of said spring o^2 serving 80 to press said slide downward, which downward movement is limited by the round nut n^3 coming in contact with the finger p , secured to the front of the ear L^2 in a fixed position, as shown in full lines in Figs. 1 and 2 85 and in dotted lines in Fig. 4, the finger p being so located as to prevent injury to the channel-knife, and the spurs by coming in contact with the work-supporting table when the machine is operated without work resting 90 upon said table.

The segmental arm M' of the lever M has formed thereon, between the slide O and its hub, a lug or block p' , which projects beyond the outer face of said slide or toward the right 95 of Figs. 1, 2, and 5, upon the outer curved face of which is secured, by means of the clamping-plate p^2 and the bolt p^3 , the upper curved trimming-knife p^3 , which is mounted in substantially the same way as the knife j is secured to the lever L and in substantially the same curved plane. The clamping-plate p^2 has formed upon or secured to its lower edge the outwardly and downwardly projecting nose-piece r , which serves as a secondary presser- 105 foot to bear upon the work while it is being fed and while the presser-foot h^3 is raised from the work. The under or operating surface of the nose-piece r has formed at its outer corner a small downwardly-projecting lip r' , to press with greater force upon the sole in line, or nearly so, with the path of the channel-cutting knife, and said nose-piece is also provided with a sharp-pointed spur s , which projects downward therefrom in line 110 with the cut made by the trimming-cutters, 115 as shown in Figs. 4 and 11.

The channel-cutting knife-blade t is formed on the lower end of a rectangular bar t' , with its cutting-edge oblique thereto, as shown in 120 Figs. 4 and 13. The bar and knife are clamped between the clamping-plates u and u' , secured together by the bolt u^2 , the whole forming the channel-knife-holding stock, which is pivoted to the lower end of the slide O by 125 means of the cylindrical hub or shank u^3 , projecting obliquely from the back side of the plate u , and fitted to a correspondingly-oblique hole in said slide and the washer u^4 and screw u^5 , all as shown in Figs. 7, 8, 9, and 130 10. The plate u has formed upon the side thereof opposite said oblique hub u^3 and at its lower end a semi-conical boss u^6 , in the large end of which is set the screw v , upon

which is mounted the truck or roll v' , which is constructed and arranged to bear upon the tread-surface of the boot or shoe sole toward the center of its width, and the small end of 5 said semi-cone has formed upon its lower side the lug v^2 , which bears upon the sole in the path of the channel-cutter and near the edge of the sole in close proximity to the upper trimming-knife.

10 The plate u has formed in its upper portion a curved slot v^3 , which is concentric to the axis of motion of said plate, as shown in Fig. 10, and a pin v^4 is set in the slide O in position to project into said slot to serve in 15 connection with said slot to limit the movement of the channel-knife holder about the axis of the oblique hub w^3 , said pin being shown only in dotted lines in Fig. 6. The construction, arrangement, and operation of 20 the channel-knife stock are a very important part of my invention, whereby the channel-knife is automatically adjusted to the varying plane of the tread-surface of the sole being acted upon, so that whether the channel- 25 knife is acting upon the nearly-flat surface of the ball of the sole or the more rounded or curved surface of the shank of the sole the cutting-blade shall maintain substantially the same angle to the surface of the sole through- 30 out the depth of cut, being gaged by contact of the lug v^2 with the upper surface of the sole.

35 P is a lever mounted upon the fulcrum-pin k' and carrying at its free end the roll w , which is acted upon by the cam-surface w' , formed on the periphery of the cam-cylinder E. The lever P has secured thereto, near its fulcrum, the spring-arm P' , the free end of 40 which is constructed and arranged to press upon the extension n^5 of the stud n^2 when the cam w^3 raises the upper end of said lever P, thereby adding increased pressure to the slide O, and through it to the channel-knife and its 45 stock during the time that the channel-knife is being moved toward the right of Figs. 1 and 2 to cut a short section of the channel.

The machine is driven by a friction-pulley mounted upon a shaft having its bearings in the base of the column or upon the floor in 50 close proximity thereto in any well-known manner and a belt leading from a pulley on said shaft to the grooved wheel G, said friction-pulley being controlled by a treadle mounted upon the floor or the base of the 55 column in any well-known manner.

The treadle, friction-pulley, and driving-shaft, forming no part of my invention, are not shown in the drawings.

60 The operation of my invention is as follows: The several parts of the machine being in the positions shown in the drawings, the operator first turns the wheel G in the direction indicated by the arrow y on Fig. 3 by hand a distance equal to about one hundred and fifteen degrees, when the trimming-knives 65 will have been moved away from each other to the extreme of said separating movements,

the presser-foot and the nose-piece r will have been raised to the extreme of their upward movements, and the pawl-lever J will have 70 been moved to the opposite extreme of its vibration from the position shown in Fig. 3 and caused the disengagement of the front pawls from the teeth of the plate g and the engagement of the rear pawls with the plate g' and 75 the bar L' with the lever M M', the channel-knife and its stock, the upper trimming-knife and its lever, and the spring-operating lever P will have been moved to the extreme of their movements toward the left of Figs. 1 80 and 2. The operator then moves the hand-lever d' against the roll d , so as to move the lever H and the table c about the fulcrum of said lever and move the bar H' toward the rear of the machine until there is sufficient 85 space between the upper surface of the free end of the table c and the point of the channel-knife t to permit the edge of the sole at the shank to be inserted between them, in which position the bar H' is locked by the 90 rear pawl and ratchet against forward movement of the same or upward movement of the table c. The operator then takes the lasted shoe with the sole secured thereto and to the last and inserts the edge of the sole at 95 the shank just in front of the heel between the table c and the channel-knife t , with the tread-surface of the sole upward and the welt resting upon the table and the front edge of the table pressing against the upper 100 in close proximity to the welt, the heel of the shoe being toward the left and the toe toward the right of Figs. 1 and 2 when he operates the friction-clutch to cause the cam-shaft D to revolve. The first operation caused 105 by the revolution of said shaft is to cause the presser-foot to descend till the spur v^3 set therein is in close proximity to or has slightly entered the surface of the sole, when the pawl-lever J is vibrated to its central position, thereby releasing the rear pawl from 110 the ratchet-teeth of the plate g' , when the tension of the spring e' causes the bar H' to be moved toward the front of the machine, thereby raising the front end of the table c 115 with the work thereon until the upper surface of the sole comes in contact with the lower end of the presser-foot, which in the meantime has continued to descend until it has nearly reached its lowest position, when 120 the pawl-lever J completes its vibration toward the front of the machine and the front pawl engages with the teeth of the ratchet-plate g and firmly locks the table c against 125 downward movement. When the presser-foot completes its downward movement and firmly clamps the sole and the bar L' with the lever M M', the channel-knife and its stock with the gage-lug v^2 , and the roll v' resting upon the sole, the former near the edge of the sole 130 and the latter about three-fourths of an inch (more or less) nearer the center of the sole, the upper trimming-knife and its lever and spring-operating lever P are moved to-

ward the right of Figs. 1 and 2 to the positions shown in the drawings, the channel-knife during such movement cutting a short section of a channel. When the last-mentioned movement is completed, the two trimming-knives are moved toward each other simultaneously to trim a short section of the sole edge, at which time the several parts have assumed the positions shown in the drawings, and as the shaft D continues its motion about its axis the presser-foot commences to rise, the lower trimming-knife begins to descend, the pawl-lever J is moved to the center of its vibration to release the front pawl from the ratchet g, and the spring-arm P' of the lever P is raised from contact with the extension n⁵ of the stud n². When the presser-foot has been raised, so as to withdraw the spur i³ from the sole, the bar L' with the lever M M', the channel-knife with its stock, the upper trimming-knife, the lever P, and spring-arm P' are moved toward the left of Figs. 1 and 2 to feed the shoe, the nose r, the gage-lug v², and roll v' resting upon the surface of the sole, and the spur's being within the sole and the channel-knife and the upper trimming-knife being within the cuts last made thereby and aiding by their friction in the feeding of the shoe. When the feeding of the shoe is completed, the upper trimming-knife is raised and the pawl-lever J completes its rearward vibration and causes the rear pawl to engage with the ratchet g' and lock the table against farther upward movement. These operations may be repeated at each revolution of the shaft D until the sole has been channeled from the heel on one side around the toe to the heel on the opposite side and the sole-edge has been trimmed for the same distance to a uniform distance from the upper, during which time the channel-knife is automatically maintained at a uniform angle to the portion of the sole upon which it is acting for the time being by the swiveling of its stock about the oblique axis thereof, caused by the pressure of the roll v' and the lug v² upon the surface of the sole, and by virtue of the oscillating movement of said stock the channel will be formed in the shank at a somewhat greater distance from the edge of the sole than around the ball and toe of the sole, which is a very desirable thing to do.

The object of mounting the channel-knife holder or stock in an oblique bearing is to keep the axis of oscillation of said stock as low as possible and at the same time keep the lower end of the slide O at such an elevation that it shall not come in contact with the sole of the shoe to its injury while cutting the channel in the shank.

What I claim as new, and desire to secure by Letters Patent of the United States, is—

1. In a machine for channeling boot or shoe soles after they are secured upon the last, the combination of a work-support to receive the welt side of the sole-edge, a presser-foot to rest upon the tread-surface of the

sole, a channel-cutting tool, a holder for said tool provided with two bearing-surfaces independent of the main presser-foot arranged to rest upon the sole, one near its edge and the other nearer the center of its width, said tool-holder being mounted upon a pivot located above said bearing-surfaces with its axis in a vertical plane between said bearings, whereby said tool-holder is made to automatically accommodate itself to the varying surface of the sole and maintain the channel-cutting tool at a uniform angle to the surface of said sole, substantially as described. 70 75 80

2. In a machine for channeling boot or shoe soles while secured upon the last, the combination of a work-support, a main presser-foot arranged to bear upon the sole opposite to the work-support, a vibrating lever 85 provided with a nose-piece or supplementary presser-foot, a spur to enter the sole carried by said nose-piece, a channel-cutting tool, a stock or holder for said cutting-tool pivotally mounted and provided with a gage-lug to bear upon the sole near its edge, and a roll or trunk mounted upon said stock and arranged to bear upon the sole at a distance from said gage-lug toward the center of the sole. 90 95

3. In a sole-channeling machine, the combination of an automatically-adjustable work-support, the vertically-reciprocating presser-foot h³, provided with the spur i³, the lever M M', the nose-piece or supplementary presser-foot r, carried by said lever, a cam for vibrating said lever, the slide O, carried by said lever M M', a spring for pressing said slide downward, the channel-cutting tool t t', the tool-carrier u u', pivoted to the slide O and provided with the gage-lug v², and the truck v', all constructed, arranged, and adapted to operate substantially as described. 100 105

4. In a machine for channeling and trimming the edges of boot or shoe soles after being secured upon the last, the combination, with an automatically-adjustable and locked work support or table, of the presser-foot h³, the lever K, carrying said presser-foot, a cam for vibrating said lever, the lever M M', 110 mounted upon a horizontally-movable fulcrum, the segmental slide O, mounted in a bearing in said lever, a spring for pressing said slide downward, a stop to limit said downward movement, a nose-piece or secondary presser-foot formed upon or carried by said lever, a cam for vibrating said lever, a channel-cutting tool, the tool-carrying stock u u', pivoted to the slide O and provided with the gage-lug v², and the roll v', mounted upon 115 120 125 said stock, a trimming-knife j', carried by the lever M M', the lever L, the trimming-knife j, carried by said lever L, a cam for vibrating said lever, and a cam and lever for moving said lever M M' laterally, substantially as described. 130

5. In a machine for channeling boot or shoe soles, the combination of a pivoted and oscillating work support or table, a movable

bar connected thereto and provided with two sets of ratchet-teeth the shoulders of which face in opposite directions, a spring connected to said bar and arranged and adapted to move 5 said bar and work-support in one direction, a pawl-lever, a cam for vibrating said lever, and two pawls mounted upon opposite ends of said pawl-lever, with their operating ends facing in opposite directions, whereby the said 10 work-support may be automatically locked in a raised or depressed position.

6. The combination, in a sole-channeling machine, of the pivoted work-support H c, the bar H', connected to said support, the 15 spring e', the hand-lever d' and roll d for moving the work-support against the tension of said spring, the two opposing sets of ratchet-teeth g and g', formed upon or secured to the bar H', the lever J, the two opposing 20 pawls h and h', carried by said lever J, a cam for vibrating said lever, the slide L', the lever M M', carried by said slide, a cam for vibrating said lever, a cam and lever for re-

ciprocating said slide and moving said lever laterally, the segmental slide O, mounted in 25 a curved bearing in said lever M M', the nose-piece r r', carried by said lever, the knife stock or holder u u', pivoted to the lower end of the slide O and provided with the gage-lug v², the channel-knife t and the roll 30 v', carried by said stock or holder, the spring o², the lever P, provided with the spring-arm P', a cam for vibrating said lever P, the stud n' n⁵, set in the slide O and engaged by the spring P, and a fixed stop constructed and 35 arranged to limit the downward movement of said slide O, substantially as described.

In testimony whereof I have signed my name to this specification, in the presence of two subscribing witnesses, on this 15th day of 40 December, A. D. 1890.

JOHN B. HADAWAY.
